UNITED STATES PATENT OFFICE.

MILTON N. HARRIS, OF LONDON, ONTARIO, CANADA.

TRAY FOR CHAIRS.

1,285,146.

Specification of Letters Patent. Patented Nov. 19, 1918.

Application filed September 3, 1918. Serial No. 252,456.

To all whom it may concern:

Be it known that I, MILTON N. HARRIS, a subject of the King of Great Britain, residing at London, in the Province of Ontario, and Dominion of Canada, have invented certain new and useful Improvements in Trays for Chairs, of which the following is a specification.

This invention relates to chair trays, and more particularly to trays for use upon infants' high chairs.

The object of the invention is to provide a simply constructed, sanitary tray of this character which may be easily removed and replaced and which is composed of material capable of being thoroughly cleansed and sterilized.

Another object is to provide an improved attaching means for the tray, which while not easily releasable by a child may be quickly and easily released by a person familiar with the operation and having the necessary strength.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:

Fig. 1 represents a top plan view of a tray constructed in accordance with this invention shown applied to the arms of a chair which latter are broken off for convenience in illustration.

Fig. 2 is a transverse section taken on the line 2—2 of Fig. 1.

Fig. 3 is a similar view taken on the line 3—3 of Fig. 1.

Fig. 4 is a detail sectional view through one end of the tray, and

Fig. 5 is a detail horizontal section through the same end as that shown in Fig. 4.

In the embodiment illustrated, the tray 10 constituting this invention is shown applied to two arms 1 and 2, which are preferably those of an infant's high chair, although obviously the tray may be applied to any other chair. Fixed to the upper face of arm 2 is a casting 3 secured by screws or otherwise, and which has an upwardly offset forwardly extending arm 4 apertured

to receive a pintle 5 carried by one end of the tray 10 so that said tray may be swung on said pivot. This pivot has a laterally extending lug 6 on its free end which is designed to pass through a slot 7 in the arm 4 of the casting 3, said slot being arranged transversely of said arm as shown in Fig. 5 so that when the pintle is inserted, this lug 6 will pass under the lower face of arm 65 4 and hold the tray against accidental removal, it being necessary to bring the lug and slot into register before the tray can be lifted.

The tray 10 which is preferably constructed of enameled iron or other metal, to render it unbreakable and yet sanitary, is shown substantially arcuate in form, although obviously it may be of any desired configuration and it has a depression 10' at 75 the center thereof to form a food receptacle, while its edge is equipped with an upstanding rib 10" to prevent the child from pushing things off the tray. An apertured ear 8 extends laterally from the inner edge of 80 the ends of the tray opposed to that which carries the pintle 5 and the aperture in said ear is designed to register when the tray is in operative position with the socket 9 formed in the upper face of the chair arm 85 1 as is shown clearly in Fig. 2. When this ear is in this position, a spring pressed latch member 11 is passed through the ear into the socket and reliably holds the tray in operative position. This latch member 11 as 90 shown is in the form of an inverted J with a bill or hooked portion 12 thereof slideable through the apertured ear 8 and adapted to enter the socket 9. The shank 11' of this latch member extends through the chair arm 95 and depends below its lower face, wear plates 13 and 14 being arranged around the aperture through which said shank passes as is shown clearly in Figs. 1 and 2. A coiled spring 15 is mounted on this shank 100 between the wear plate 14 on the lower face of the arm 1 and a washer 16 held on the free end of the shank by a nut 17 or any other securing means. This coiled spring exerts its tension to hold the latch in operative 105 engagement with the tray and the spring is made of sufficient strength so that a child cannot lift the latch to release the tray.

When it is desired to disengage the latch from the chair, all that is necessary is to 110 grasp the curved bill portion and lift it into the dotted line position shown in Fig. 2 or

this latch may be raised by engaging the washer 16 on its lower end and forcing the shank upwardly against the tension of the spring 15. When this bill has been moved 5 out of engagement with the ear 8, the tray may be swung on its pintle 5 to release the child, and if desired, may be removed in the manner above described.

A tray constructed in accordance with 10 this invention is thoroughly sanitary, not breakable, may be cheaply manufactured and readily applied to chairs already in use, and it will be very efficacious for the purpose for which it is intended.

15 The foregoing description and the drawings have reference to what may be considered the preferred or approved form of my invention. It is to be understood that I may make such changes in construction and 20 arrangement and combination of parts, materials, dimensions, etc., as may prove expedient and fall within the scope of the claimed invention.

Having thus fully described my invention, 25 what I claim as new and desire to secure by Letters Patent, is:—

1. The combination with a chair having arms; of a casting secured to one of said

arms and provided with an upwardly off-set apertured extension, a tray having a 30 pintle at one end for engagement with said extension and a laterally extending apertured ear at its other end, and a spring 35 pressed latch carried by the other arm of the chair and adapted to enter the apertured ear of the tray for locking the tray in operative position.

2. The combination with a chair having arms, one of which has an aperture extending therethrough and a socket in its upper 40 face spaced from said aperture and a casting secured to the other arm and provided with an extension, an inverted J-shaped latch having the shank thereof mounted in said aperture and its bill positioned to enter 45 said socket, a tray having a pintle for engagement with the extension of said casting, and an apertured ear adapted to be positioned over the socket in the other arm of the chair, to receive the bill of said latch. 50

In testimony whereof I affix my signature in presence of two witnesses.

MILTON N. HARRIS.
